UNITED STATES PATENT OFFICE

152,265

DESIGN FOR A RAILROADER'S CAP

Andrew O. Hatleli, Grand Forks, N. Dak.

Application November 13, 1947, Serial No. 142,505

Term of patent 7 years

(Cl. D3—13)

To all whom it may concern:

Be it known that I, Andrew O. Hatleli, a citizen of the United States, residing at Grand Forks, in the county of Grand Forks and State of North Dakota, have invented a new, original, and ornamental Design for a Railroader's Cap, of which the following is a specification, reference being had to the accompanying drawing, forming part thereof.

The figure is a perspective view of a railroader's cap, showing my new design.

The stitching extends to the back of the cap as would appear obvious from the front stitching.

I claim:

The ornamental design for a railroader's cap, as shown and described.

ANDREW O. HATLELI.
